FOLDING DRAWBAR FOR SECTIONAL HARROWS

Bernard Landen, Ida Grove, Iowa

Application May 21, 1945, Serial No. 594,917

4 Claims. (Cl. 55—84)

1

This invention relates generally to draw bars and in particular to a draw bar for sectional harrows.

Draw bars for sectional harrows generally comprise a central section and end sections hinged or pivoted to the central section for pivotal up and down movement. These draw bars are usually connected with the tractor unit through cables, chains, or the like adapted to be under tension when the sections are in longitudinal alignment. However, on the advance of the draw bar over an uneven ground surface, such that the end sections are pivoted upwardly, the cables connected with the end sections become slack due to the decreased distance between the cable connections on the tractor unit and the cable connections on the end section. As a result the load normally carried by the end section cables is transmitted to the pivoted connections between the end sections and the central section so that the pivoted connections carry the full load or drag on the end sections.

Since this load is applied on the pivoted connection through a simple lever arm having a length corresponding to the length of the end section, the end section is oftentimes bent rearwardly from its pivoted connection, or the pivoted connection is completely broken. Attempts to overcome these difficulties have resulted generally in unwieldy and bulky draw bars which are not too satisfactory in operation, and are clumsy to handle.

It is an object of this invention, therefore, to provide an improved draw bar.

A further object of this invention is to provide a sectional draw bar which is of a construction adapted to maintain the cables, connecting the draw bar end sections with a tractor unit, under tension at upward pivotally moved positions of the end sections so that such cables always carry a part of the load on the end sections.

A feature of this invention is found in the provision of a sectional draw bar, in which the end sections are movably connected with the central section for up and down pivotal movement and for rearward and forward movement so that cables connecting the end sections with a tractor unit are maintained under a substantially normal tension on upward movement of the end sections relative to the central section, whereby to keep the full load on an end section from being applied on its connection with the central section.

Another feature of this invention is found in the provision of a sectional draw bar in which the end sections are connected with the central sec-

2

tion through limited acting universal connections providing for an up and down pivotal movement and a rearward and forward movement of the end sections relative to the central section, and constructed to limit the downward pivotal movement of the end sections to positions in a plane substantially common to the central section.

Further objects, features and advantages of this invention will become apparent from the following description when taken in connection with the accompanying drawings in which:

Fig. 1 is a perspective view of the sectional draw bar of this invention;

Fig. 2 is a sectional view taken on the line 2—2 in Fig. 1 showing an end section in a moved position;

Fig. 3 is a detail perspective fragmentary view of the connection between the central section and an end section;

Fig. 4 is a longitudinal sectional view of the connection shown in Fig. 3;

Fig. 5 is a sectional view as seen on the line 5—5 in Fig. 4 showing parts in changed position; and

Fig. 6 is a detail perspective view of the parts forming the connection in Fig. 3, shown in positions providing for their relative assembly.

Referring to the drawings the draw bar of this invention is illustrated in Fig. 1 as including a center section 10 and end sections 11, of a pipe construction, and provided on their rear sides with hooks 12 for attachment with harrow sections. The end sections 11 are connected with the center section 10 through a ball and socket connection, indicated generally at 13, for pivotal up and down movement and for rearward and forward movement relative to the center section 12. Since the connections 13 are similar in construction and operation, only one thereof will be described in detail.

The connection 13 (Figs. 3 and 6) includes a first connection member 14 integrally formed with a cylindrical body member 16 including an annular flange 26 at one end provided with an axial extension or neck member 17 of a substantially rectangular shape in cross section and having a ball member 18 at its free end. The cylindrical body member 16 is of a diameter adapted to be received within an outer end of the center section 10. As shown in Fig. 4, one side 15 of the neck member 17 is of a concave curvature, while its opposite side 20 is of a straight line contour.

A second connecting member 21 (Figs. 3 and 6) of a substantially C-shape in cross section is

integrally formed with a clamping member 22 adapted to be positioned about the inner end 23 of an end section 11, and a socket member 24 at one end of the clamping member 22.

In the assembly of a connection 13 the connecting member 14 is initially inserted within an outer end of the central section 10 to a position defined by the abutment of the flange 26 (Fig. 4) with the end of the center section 10. The member 14 is then rotated within the center section 10 until the side 20 of the neck portion 17 is positioned at the top of the center section 10. This relative position of the connecting member 14 within the center section 10 locates the concavely curved side 15 of the neck member 17 at the bottom of the center section 10. The member 14 is then suitably fixed on the center section 10 by welding or like means.

The connecting member 21 is assembled with the connecting member 14 by initially arranging these members as shown in Fig. 6 so that the ball member 18 is receivable within the end 29 of the C-shaped clamp 22 and the neck member 17 within the open side 31 of the member 21. The connecting member 21 is then moved relative to the connecting member 14 until the ball member 18 is positioned within the socket member 24. The inner end 23 of an end section 11 is then inserted within the clamping member 22 through its end 29, after which the member 22 is fixed on the end section 11 by bolts 32 extended through aligned openings in the clamping member 22 and in the end section 11.

Referring to Fig. 4, it is seen that the socket member 24 has an end portion extended inwardly beyond the ball member 18 and provided with a curved underside 33 adapted for mating engagement with the curved underside 15 of the neck member 17 to maintain the end section 11 against downward pivotal movement out of a plane substantially common to the plane of the center section 10. On upward pivotal movement of an end section 11 the portion 33 is moved away from the neck member 17 as illustrated in dotted lines in Fig. 4. It is seen, therefore, that a ball and socket connection 13, between an end section 11 and a center section 10, provides for a pivotal movement of an end section relative to the center section from a position in substantial longitudinal alignment with the center section to an upright position substantially normal to the center section. This upright position is defined by the engagement of the top inner edge 34 of an end section 11 with the top side 20 of the neck member 11.

Also, as best appears in Fig. 5, an end section 11 is movable rearwardly and forwardly relative to the center section 10 through a limited angle defined by the engagement of the neck member 17 with the opposite edges 36 of the opening 31 at the top of the socket member 24. In one embodiment of the invention the complete angular movement of an end section relative to a center section in a forward and rearward direction is on the order of about forty-five degrees, that is, about an angle of twenty-two and a half degrees to each side of the center section.

The draw bar is connected with a suitable tractor unit (not shown) by a pair of cables or chains 37 connected at their rear ends with the center section 10 by suitable clamps 38 and at their forward ends to a hitch ring 39. The cables 37 are arranged so as to provide for a forward movement of the center section 10 in a plane normal to the line of advance of the tractor unit. A cable

or chain 41 is connected between the hitch ring 39 and the forward edge 42 of a brace or support 43 projected forwardly from the front-side of each end section 11. The member 43 is of a substantially rod form secured at one end 44 to the outer end of an end section 11. From its end 44 the member 43 is extended inwardly and forwardly of the draw bar and then bent rearwardly for connection at 45 with the front side of an end section 11, with the rearward bend in the member 43 constituting the forward edge 42. When the draw bar sections 10 and 11 are in longitudinal alignment, the cables 37 and 41 are maintained under tension as the tractor unit is advanced.

Draw bars of the type covered by this invention generally have their end sections connected with a center section for up and down pivotal movement in the longitudinal plane of the center section as illustrated in dotted lines in Figs. 1 and 2 for an end section 11' having a cable 41' connected with the hitch ring 39. Further, the cable 41' connecting the end section with a tractor unit usually has its rear end 40 attached directly to the front side of the end section 11'. In the use of these draw bars, therefore, on travel of the end section 11' over a ground surface at a higher elevation than the center section the end section 11' is pivoted upwardly in a straight line movement so that the cable 41' becomes slack as also illustrated in dotted lines in Figs. 1 and 2.

As a result any drag or load on the end section 11' is applied in full on the pivoted connection 13' between the end section 11' and the center section. This load oftentimes is sufficiently great to either bend the end section 11' rearwardly from its pivoted connection, or break the pivoted connection. Also where the cable 41' is attached directly to the front side of an end section loads may be incurred which, during a normal advance of the end section in longitudinal alignment with the center section, will bend the end section rearwardly from its point of attachment with the cable 41'.

In the operation of the draw bar of this invention, on advance of an end section 11 over a ground surface at a higher elevation than the center section 10, the end section 11 is concurrently pivoted upwardly and moved rearwardly, as illustrated in Fig. 2, by virtue of the ball and socket connection 13. Thus even though the upward pivotal movement of an end section 11 tends to decrease the distance between the connections of the cable 41 at 42 and at the hitch ring 39, this decreased cable length is accommodated by the rearward movement of the end section 11 so that the cable 41 is maintained under tension. A large portion of the load on an end section 11 is thus carried by a cable 41 so that the full load on the end section is not applied on the ball and socket connection 13. In other words, when an end section 11 is in an upwardly pivotally moved position sufficient rearward movement of the end section takes place to keep the cable 41 under tension whereby the load on an end section 11 is continuously divided between the cable 41 and the ball and socket connection 13. Since the brace rod 43 is connected with an outer end of an end section 11, the rod acts to hold the section 11 from being bent rearwardly at its connection 45 with the brace.

When the center section 10 is being advanced over a ground surface at a higher elevation than an end section 11, the end section is maintained in substantially the plane of the center section 10

by the engagement of the coating portions 15 and 33, in a connection 13, so as to prevent the end section 11 from digging into the ground and producing a twisting action on the connection 13.

From a consideration of the above description, it is seen that the invention provides a sectional draw bar which is of a simple and inexpensive construction, light in weight so as to be easily handled, and of a construction adapted to eliminate a breaking failure in an end section connection resulting from the application of a full load or drag on the end section to the connection. This is accomplished by providing for a rearward movement of an end section concurrently with its upward pivotal movement so as to maintain the cable connection between the end section and the tractor unit under tension at all times of operation. Thus, although the upward pivotal movement of an end section tends to decrease the distance between the cable connection on the tractor unit and the cable connection on an end section, the rearward movement of the end section concurrently acts to increase the distance between these cable connections. As a result, the rearward movement of an end section compensates for the upward pivotal movement of an end section so as to maintain the distance between the cable connections substantially constant for all upwardly moved positions of the end section.

Although the invention has been described with respect to a preferred embodiment thereof, it is to be understood that it is not to be so limited since changes and alterations can be made therein which are within the full intended scope of this invention as defined by the appended claims.

I claim:

1. A draw bar for harrows comprising a center section and end sections, means movably connecting the end sections with said center section for pivotal up and down movement and for rearward and forward movement, means limiting the downward pivotal movement of said end sections to a position in a plane substantially common to said center section, brace structures extended forwardly from said end sections, means connecting said end sections with a tractor unit including flexible means connected between the tractor unit and the forward edges of said brace structures, said flexible means having a tension therein when the sections are in substantial longitudinal alignment, with said tension being maintained on an upward and rearward pivotal movement of said end sections.

2. A draw bar for harrows comprised of a center section and end sections, means movably connecting said end sections to the center section for up and down pivotal movement and for rearward and forward movement including ball members at opposite ends of said center section, neck portions connecting said ball members with the center section, socket members at the inner ends of said end sections adapted to receive said ball members, said socket members having open top sides, and bottom sides extended inwardly for

bearing engagement with the underside of said neck portions to limit the downward pivotal movement of said end sections to positions in a plane substantially common to said center section, and means connecting said sections with a tractor unit including flexible means connected with said tractor unit and said end sections, with said flexible means adapted to be under tension when said sections are in said common plane, and said tension being maintained on pivotal and rearward movement of said end sections.

3. A draw bar for harrows including a center section and an end section of a pipe construction, means movably connecting the inner end of said end section and the outer end of said center section for up and down pivotal movement and rearward and forward movement of said end section relative to said center section including a first connecting member receivable in one of said two ends, a longitudinal projection on said first connecting member having a ball portion at the free end thereof, a second connecting member of a substantially C shape in cross section mounted about the other of said two ends having a socket portion adapted to receive said ball portion, with the top side of said C connecting member being open and the bottom side of said socket portion adapted for bearing engagement with the underside of said neck portion to limit the downward pivotal movement of said end section to a position in substantially the plane of the center section, and means connecting said two sections with a tractor unit including a flexible means connected with the end section adapted to have a tension therein when the two sections are in longitudinal alignment, with said tension being retained on pivotal and rearward movement of said end section.

4. A draw bar for harrows comprising a center section and an end section, a ball and socket connection including a ball member on one of said sections and a socket member on the other of said sections for connecting the end section to the central section for pivotal up and down movement and for forward and rearward movement, means including co-acting stop portions on the ball and socket members of said connection for limiting the downward pivotal movement of said end sections to positions in a plane substantially common to said center section, and means for connecting said sections to a tractor unit including flexible means connected with said end sections at positions such that said flexible means are under tension when said end sections are in said common plane and in rearwardly moved positions therefrom.
